UNITED STATES PATENT OFFICE.

JAMES R. FRENCH, OF LOMAX, ILLINOIS

PISTON-ROD.

1,218,074.

Specification of Letters Patent.

Patented Mar. 6, 1917.

Application filed February 24, 1916. Serial No. 80,293.

To all whom it may concern:

Be it known that I, JAMES R. FRENCH, a citizen of the United States, residing at the town of Lomax, county of Henderson, and State of Illinois, have invented certain new and useful Improvements in Piston-Rods, of which the following is a specification.

This invention relates to piston rods, more particularly to such as are used in connection with internal combustion motors, to connect the piston with the crank shaft.

An object of this invention is to provide an improved construction wherein provision is made for compensating for any wear in the bearings, whether of the bushings carried by the rod, or of the pin to which it is attached.

With the foregoing and other objects in view, the invention consists of the novel construction and arrangement of parts illustrated in the accompanying drawing, which forms a part of this specification, wherein is set forth an embodiment of the invention, but it is to be understood that such changes and modifications may be resorted to as come within the scope of the appended claims.

Referring now to the drawing wherein similar reference characters designate like parts in the several views: Figure 1, is a side elevation of an embodiment of the invention, with parts broken away to show the construction: Fig. 2, a front elevation: Fig. 3, a central vertical section, on an enlarged scale, on line 3—3 of Fig. 1: Fig. 4, a transverse section on line 4—4 of Fig. 1: Fig. 5, a perspective view of the lower end of the rod with the strap removed: Fig. 6, a perspective view of the strap which fits over the lower end of the rod:

Referring now more particularly to the drawing the reference character —10— designates a rod, the stem, or body —11— of which may be of any desired shape. At the lower end of the stem is an enlargement —12— which projects beyond the sides of the rod, forming shoulders —13—. The opposite faces —14— of the enlargement are plane surfaces which lie in substantially the same planes as the edges of the rod. Disposed across the lower end of the rod is a bearing —15— which is adapted to receive the upper half —16— of a bushing which may be of usual or any suitable pattern. A strap —17— which fits over the lower end of the rod carries the lower half —18— of the

bushing. The sides —19— and wings —20— of the strap parallel, but are spaced from the sides respectively, of the bearing 15 and the enlargement 12. A pair of tapering, or wedge shaped shims —21, 22— are interposed between the wings and sides of the strap and the rod, the largest, or butt end of the outer shim 21 rests upon ledges, or shoulders —23— on the inner side of the strap. The outer sides of the wings 20, are arcs of a circle, the radius of which is a little greater than that of the edges of the enlargement 12 on the rod, and are provided with screw threads —24. A sleeve —25— provided with internal screw threads —26— is disposed about the body 11, and engages with the threads 24 on the strap. An internal shoulder —27— on the sleeve bears on the shoulders 13, of the enlargement 12, on the rod. It is obvious that with the sleeve resting on the shoulder 27, and engaged with the threads on the strap, the strap can be adjusted to and fro relative to the rod by turning the sleeve. The butt end of the inner shim 22 bears against the shoulder 27 of the sleeve. The office of the shim is to prevent any lateral movement of the strap relative to the rod, due to wear. A spring —28— coiled about the rod is adapted to have its free end —29— engaged in recesses —30— in the upper edge of the sleeve and tends to exert a constant tension thereon to prevent retrograde movement of the sleeve.

In service any wear of the bushings, or the crank pin, may be taken up by turning the sleeve to draw the straps up. The use of a strap to hold bushings in contact with a bearing pin is well known, but the arrangement set forth herein for drawing the strap up and taking up any wear of bushings or crank pin is new.

Having thus described my invention so that anyone skilled in the art pertaining thereto may make and use the same,

I claim:

1. A piston rod comprising a stem, a strap having screw-threaded wings embracing an end thereof, a screw threaded sleeve disposed about said stem and engaged with the screw threads on the strap, said sleeve being provided with a plurality of radial slots, and a resilient element connected with the stem and adapted to be engaged in any one of said slots.

2. A piston rod, comprising a stem, or

- body, a strap embracing an end thereof, a sleeve disposed about said stem and engaged with said strap to draw the same up against the end of the rod, said sleeve being provided with a plurality of openings at the upper end thereof, and a resilient element connected with the stem and adapted to be engaged in any one of said openings.
3. A piston rod, comprising a stem, or body, a strap embracing an end thereof, a sleeve disposed about said stem and engaged with said strap to draw the same up against the end of the rod, said sleeve being provided with a plurality of openings at the upper end thereof, and a coil spring disposed about the stem and adapted to be engaged in any one of said openings.
4. A piston rod comprising a stem, or body, a strap having wings embracing an end thereof, a sleeve disposed about said stem and the wings of said strap, and engaged with the strap to draw the same against the end of the stem, and means adjustably engageable with the sleeve to exert forward pressure thereon.
5. A piston rod comprising a stem, or body, a strap having screw threaded wings embracing an end thereof, and a screw threaded sleeve disposed about said stem and

engaged with the screw threads on said strap.

6. A piston rod comprising a stem, or body, a strap having wings embracing an end thereof, and tapering shims between the wings of said strap and the body of the rod.

7. A piston rod comprising a stem, or body, a strap having wings embracing an end thereof, and a pair of oppositely disposed tapering shims disposed between each of the wings of the strap and the body of the rod.

8. A piston rod comprising a stem, or body, a strap having wings embracing an end thereof, means disposed about said stem and engaged with said strap to draw the same up against the rod, and tapering shims disposed between the wings of said straps and the body of the rod.

9. A piston rod comprising a stem, or body, a strap having wings embracing an end thereof, means disposed about said stem and engaged with said strap to draw the same up against the rod, and oppositely disposed tapering shims disposed between each of the wings of said strap and the body of the rod.

JAMES R. FRENCH.
